(57) **CLAIM**

The ornamental design for a dog training device set, as shown and described.

DESCRIPTION

FIG. 1 is a perspective view of a dog training device set consisting of a remote controller and a receiver according to the present application;

FIG. 2 is an upper perspective view of a dog training device set, with the remote controller shown in isolation for clarity of disclosure;

FIG. 3 is a lower perspective view of the remote controller of FIG. 2;

FIG. 4 is a front elevational view of the remote controller of FIG. 2;

FIG. 5 is a rear elevational view of the remote controller of FIG. 2;

FIG. 6 is a left side elevational view of the remote controller of FIG. 2;

FIG. 7 is a right side elevational view of the remote controller of FIG. 2;

FIG. 8 is a top plan view of the remote controller of FIG. 2; FIG. 9 is a bottom plan view of the remote controller of FIG. 2;

FIG. 10 is an upper perspective view of a dog training device set, with the receiver shown in isolation for clarity of disclosure;

FIG. 11 is a lower perspective view of the receiver of FIG. 10;

FIG. 12 is a front elevational view of the receiver of FIG. 10; FIG. 13 is a rear elevational view of the receiver of FIG. 10; FIG. 14 is a left side elevational view of the receiver of FIG. 10;

FIG. 15 is a right side elevational view of the receiver of FIG. 10;

FIG. 16 is a top plan view of the receiver of FIG. 10; and, FIG. 17 is a bottom plan view of the receiver of FIG. 10. The broken lines in the drawings depict portions of the dog training device set that form no part of the claimed design.

1 Claim, 17 Drawing Sheets
